UNITED STATES PATENT OFFICE.

CHARLES E. LUCKE, OF NEW YORK, N. Y.

METHOD OF BURNING LIQUID OR GASEOUS FUELS.

SPECIFICATION forming part of Letters Patent No. 755,377, dated March 22, 1904.

Application filed July 30, 1901. Serial No. 70,230. (No model.)

To all whom it may concern:

Be it known that I, CHARLES E. LUCKE, a citizen of the United States, residing at New York city, county of New York, and State of New York, have invented certain new and useful Improvements in Methods of Burning Liquid or Gaseous Fuels, fully described and represented in the following specification and the accompanying drawings, forming a part of the same.

This invention relates to the combustion of gaseous and liquid fuel.

The invention aims especially to provide an improved method of burning oils, although the method is applicable to other liquid fuels and in part to gaseous fuels.

The use of liquid and gaseous fuels has heretofore been limited by reason of the methods employed in burning the same being unsatisfactory and unsuitable for various purposes. By my improved method, however, I am enabled to obtain by the use of such fuels substantially the same results as can be obtained by the use of solid fuels, such as, coal and coke. For many purposes for which a coal fire has been heretofore used it is desirable and necessary to have a flame extending a considerable distance beyond the bed of the fire and to be able to control such flame. By my invention I am enabled to secure this result with liquid or gaseous fuels.

In burning liquid fuel, such as oil, in accordance with my invention the oil or other liquid fuel and a suitable combustion-sustaining gas, such as air, are caused to flow into a hot combustion-bed, which is formed, preferably, by a mass of pieces or fragments of a suitable refractory material. As the oil enters this hot combustion-bed it is vaporized, and the vapor mixing with the air is ignited and the combustion takes place within the bed. As the gaseous mixture of oil-vapor and air flows through such a combustion-bed its direct advance will be prevented and it will be caused to spread out through the subdivided passages of the bed, and thus to advance in increasing volume and with diminishing velocity and without diffusion with other gas, as described in my application filed in the United States Patent Office June 7, 1901, Serial No. 63,549, and if

sufficient air is fed to the combustion-bed for the complete combustion of the oil fed to the combustion-bed and they are admitted in such quantity as to be within the capacity of the combustion-bed and in such a manner that the mixture will move with an initial velocity greater than the rate of propagation of inflammation through the mixture then the fuel will be completely burned within the combustion-bed, the combustion taking place at the surface of constant velocity in accordance with the method of my said application and as more fully explained therein. The combustion-bed may be formed in any suitable manner to cause the gaseous mixture as it flows therethrough to advance in increasing volume and with diminishing velocity. I have found, however, a bed of loose pieces or fragments of refractory material to answer the purpose well and prefer to use the same. It will be understood, however, that by the term "combustion-bed," as used in the claims, I mean a bed of suitable material so arranged as to permit the gaseous mixture of fuel and air or other combustion-supporting gas to flow therethrough and to cause the mixture as it flows therethrough to advance in increasing volume and with diminishing velocity and without diffusion with other gas. For obtaining a flame beyond the surface of the combustion-bed I supply the oil and air to the combustion-bed in proportions such that there is not sufficient air for the complete combustion of the oil, but still sufficient to give the resulting gaseous mixture the property of self-propagation of inflammation. The oil-vapor will then be partially consumed within the combustion-bed and the remainder passing through the bed will burn at and beyond the surface of the bed, forming a longer or shorter flame, according to the proportions in which the oil and air are fed to the bed and according as the flame is influenced by outside conditions. This combustion at and beyond the surface of the bed will be sustained by oxygen from the surrounding atmosphere or from air or other suitable gas fed to the flame in any suitable manner, or as now practiced in connection with coal or coke fires. It is necessary that the bed should be hot in order to vaporize the

oil. For starting the fire the bed may be heated in any suitable manner. For example, a gaseous fuel may be used for heating the bed, or I may employ at the start a bed of 5 burning coal or coke and afterward maintain this bed by the addition of fresh coal or coke, thus employing my method in conjunction with an ordinary coal or coke fire, or I may after starting with coal or coke add loose 10 pieces of suitable refractory material to form a permanent bed as the coal burns away. When a gaseous fuel is employed, the process of burning it will correspond to the above with the omission of the step of vaporizing 15 fuel. The fuel and air or other combustion-sustaining gas may be fed to the combustion-bed separately, so as to be mixed therein, or may be fed together through a single nozzle or nozzles, as may be desired. 20 The accompanying drawings illustrate several ways in which my method may be carried out and several applications of the same. It will be understood, however, that such apparatus as I have shown in the drawings is shown 25 merely by way of example and for the purpose of disclosing suitable means for carrying out the method and illustrating some of the uses to which the method is applicable.

In said drawings, Figure 1 illustrates a simple form of burner which may be used in burning liquid or gaseous fuels in accordance with my invention. Fig. 2 shows a modified form thereof. Figs. 3, 4, and 5 illustrate apparatus for employing my improved process, being, 30 respectively, a crucible furnace, a reverberatory furnace, and a steam-boiler furnace in which gaseous or liquid fuels are to be burned in accordance with my invention, Fig. 3 also showing a simple form of apparatus for supplying liquid fuel and a combustion-supporting gas to the furnace.

Referring to Fig. 1, the fuel and the combustion-supporting gas are admitted in proper proportions through a comparatively small 45 inlet-opening 2, and above the inlet-opening the walls of the burner are spread apart to form a space of gradually-increasing transverse area, and the space between these spreading walls is filled with small pieces of suitable 50 refractory material placed loosely therein to form a combustion-bed 3. In using this burner the fuel and combustion-supporting gas are supplied to the inlet-opening 2 by any suitable means, and if the fuel is a liquid it will 55 be vaporized (assuming the combustion-bed 3 to be sufficiently heated) and the vapor will mix with the combustion-supporting gas, and the mixture rising through the combustion-bed will be caused to spread out and advance 60 with diminishing velocity. Combustion will then take place within the bed, and if the proportions of the fuel and combustion-supporting gas are such that there is not enough gas for the complete combustion of the fuel combustion will also take place at and beyond the 65

surface of the combustion-bed, as heretofore explained. If a gaseous fuel is employed, the action will be the same, except that there will be no vaporizing of the fuel. In Fig. 2 the fuel and combustion-supporting gas are fed to 70 the combustion-bed 3 through separate nozzles 4 and 5. With this burner, if the fuel is a gas, the mixing of the fuel-gas and combustion-supporting gas will take place within the bed, and if the fuel is a liquid it will be vaporized as before, and the vapor will then mix with the combustion-supporting gas. With 75 both of these burners, if a gaseous fuel is used, no preliminary heating of the combustion-bed will be required. If an easily-vaporized liquid 80 fuel is used, it will be necessary only to provide means for vaporizing the same at the start as it passes through the nozzle 4. If, however, a liquid fuel which is not readily vaporized is used, as a heavy oil, it will be necessary 85 to provide for a primary heating of the combustion-bed. This can be accomplished in any suitable manner, as by using a gaseous fuel or by using a bed of burning coal, as before explained. By varying the proportions 90 of the fuel and combustion-supporting gas the flame extending beyond the bed may be varied, as before pointed out.

Fig. 3 shows a simple form of crucible furnace for burning liquid or gaseous fuel in accordance with my invention. The combustion-bed 3 is located in the bottom of the furnace, and the fuel and combustion-supporting gas are admitted through pipes 6 and 7, which are connected to the nozzle 8, which extends 95 into the combustion-bed. The opening 9 is provided for admitting air above the combustion-bed for sustaining the combustion above the bed. In the apparatus shown in this figure for supplying the constituents of the 100 gaseous mixture to the furnace, O represents a tank for oil or other liquid fuel and A a tank for air or other combustion-supporting gas, the air being supplied to this tank by any suitable means adapted to maintain the desired pressure therein. The pipe 6 connects the oil-tank O and the pipe 7 with the air-tank A, and the pipes 6 and 7 are provided with valves *o* and *a*, respectively. By means 105 of the valve *o* the flow of oil to the nozzle 8 may be controlled according to the amount of air passing through the pipe 7 to secure the proper proportion of oil to air, and by the valve *a* the flow of air to the nozzle may be controlled to cause the air to enter the combustion-bed with sufficient velocity to secure 110 a movement of the resulting gaseous mixture from the point of mixing with a velocity greater than the rate of propagation of inflammation of the mixture. The proper proportions of oil and air or other combustion-supporting gas—that is, proportions such according to the nature of the constituents that the gaseous mixture resulting from the mixing 115 of the oil-vapor and air will have the 120

property of self-propagation of inflammation—and the necessary velocity of flow of air through the nozzle may be readily determined by experiment.

5. Fig. 4 shows the application of the invention to a reverberatory furnace. As here shown, the fuel and combustion-supporting gas are fed to the combustion-bed 3 through the nozzle 8, and air is admitted through an opening 9 for sustaining combustion above the combustion-bed.

Fig. 5 shows the application of the invention to a steam-boiler furnace. Two combined fuel and combustion-supporting gas inlet nozzles 8 are shown leading to the combustion-bed 3 from below.

I have found that by my method a very perfect combustion of both light and heavy oils may be secured, and by varying the proportions of oil and air supplied to the combustion-bed the character of the fire may be readily varied from one having no surface flame to one having a surface flame of almost any desired length. Moreover, the character of the flame may be varied in the manner now practiced with coal fires. This perfect combustion, combined with the production of a surface flame changeable at will both in length and character, is extremely important in many industrial operations. It should also be noted that by reason of the hot bed of solid matter I obtain a steadiness of heating power which it is impossible to secure by the methods heretofore employed for burning liquid and gaseous fuels and which has heretofore been attainable only with coal or other solid fuel.

What I claim is—

1. The method of burning fluid fuel which consists in causing the fuel and a suitable combustion-supporting gas in proportions such that there will be an excess of fuel over the quantity required for perfect chemical combination with the oxygen of the supporting-gas to flow into a hot combustion-bed, the supporting-gas moving with such velocity as to cause the resulting mixture to move with a velocity greater than the rate of propagation of inflammation through the mixture, and the combustion-bed being of such a nature as to cause the mixture to spread out so that the successive surfaces of uniform velocity shall have adjacent points in any such surface at substantially the same distance from the place where the spreading begins, thereby reducing the velocity of the mixture to the rate of propagation of inflammation and preventing diffusion with other gas; and burning within the bed so much of the fuel as therein forms with the supplied oxygen an explosive gaseous mixture and burning at or beyond the surface of the bed the remainder of the fuel, substantially as described.

2. The method of burning liquid fuel which consists in causing the fuel and a suitable combustion-supporting gas in proportions such

that there will be an excess of fuel over the quantity required for perfect chemical combination with the oxygen of the supporting-gas to flow into a hot combustion-bed whereby the fuel will be vaporized and mix with the gas, the supporting-gas moving with such velocity as to cause the resulting mixture to move with a velocity greater than the rate of propagation of inflammation through the mixture, and the combustion-bed being of such a nature as to cause the mixture to spread out so that the successive surfaces of uniform velocity shall have adjacent points in any such surface at substantially the same distance from the place where the spreading begins, thereby reducing the velocity of the mixture to the rate of propagation of inflammation and preventing diffusion with other gas; and burning within the bed so much of the fuel as therein forms with the supplied oxygen an explosive mixture, and burning at or beyond the surface of the bed the remainder of the fuel, substantially as described.

3. The method of burning liquid fuel which consists in causing the fuel and a suitable combustion-supporting gas to flow into a hot combustion-bed whereby the fuel will be vaporized and mix with the gas, the supporting-gas moving with such velocity as to cause the resulting mixture to move with a velocity greater than the rate of propagation of inflammation through the mixture, and the combustion-bed being of such a nature as to cause the mixture to spread out so that the successive surfaces of uniform velocity shall have adjacent points in any such surface at substantially the same distance from the place where the spreading begins, thereby reducing the velocity of the mixture to the rate of propagation of inflammation and preventing diffusion with other gas, and burning the fuel at least partially within the bed, substantially as described.

4. The method of burning fluid fuel which consists in causing the fuel and a suitable combustion-supporting gas in proportions such that there will be an excess of fuel over the quantity required for perfect chemical combination with the oxygen of the supporting-gas to flow into a hot combustion-bed, the supporting-gas moving with such velocity as to cause the resulting mixture to move with a velocity greater than the rate of propagation of inflammation through the mixture, and the combustion-bed being of such a nature as to cause the mixture to spread out so that the successive surfaces of uniform velocity shall have adjacent points in any such surface at substantially the same distance from the place where the spreading begins, thereby reducing the velocity of the mixture to the rate of propagation of inflammation and preventing diffusion with other gas; and burning within the bed so much of the fuel as therein forms with the supplied oxygen an explosive mixture, and burning at or beyond the surface of the bed the

remainder of the fuel; and varying the proportions of the fuel and gas to change the character of the surface flame, substantially as described.

5. The method of burning fluid fuel which consists in causing the fuel and a suitable combustion-supporting gas to flow into a hot combustion-bed, the supporting-gas moving with such velocity as to cause the resulting mixture to move with a velocity greater than the rate of propagation of inflammation through the mixture, and the combustion-bed being of such a nature as to cause the mixture to spread out so that the successive surfaces of uniform velocity shall have adjacent points in any such surface at substantially the same distance from the place where the spreading begins, thereby reducing

the velocity of the mixture to the rate of propagation of inflammation and preventing diffusion with other gas; burning the fuel at least ²⁰ partially within the bed; and varying the proportions of the fuel and gas to change the character of the flame from one having no surface flame to one having a surface flame of greater or less length, as desired, substantially as described. ²⁵

In testimony whereof I have hereunto set my hand in the presence of two subscribing witnesses.

CHARLES E. LUCKE.
